UNITED STATES PATENT OFFICE.

ELOF KARL HJALMAR LUNDBERG, OF SALTSJOBADEN, SWEDEN, ASSIGNOR TO SESAM AKTIEBOLAG, OF STOCKHOLM, SWEDEN, A COMPANY OF SWEDEN.

WATER-CLOSET.

Application filed November 12, 1925, Serial No. 68,668, and in Sweden November 26, 1924.

This invention relates to a water closet in which complete flushing takes place even when the flushing water is supplied slowly.

In order that an effective flushing will take place in water closets now used, the flushing water must enter them at a rate of 1.5 to 2.0 liters per second. The water is brought to the closet either from a flushing cistern or through a flushing valve. In order that the requisite speed of the flushing water shall be attained if the former is the case the flushing cistern must be placed at a sufficient height above the closet, depending upon the dimensions of the flushing pipe, and in the latter case the piping to the flushing valve must be given sufficiently large dimensions. In a closet, according to the present invention, the flushing takes place quite independently of the speed with which the flushing water enters the closet.

The invention is principally characterized therein, that at or above the upper edge of that part of the outlet pipe which is enlarged into a collecting funnel is arranged a special cistern, the flushing water cistern, which entirely or partly surrounds the upper edge of the funnel and whose inner wall situated against the funnel, or a part thereof, is movable and arranged to co-operate with a tightening device so, that in one position of the wall or part of the wall, all the flushing water supplied through a float-valve, flushing valve or any other suitable way collects in the flushing water cistern, which thereby is completely closed from the funnel and outlet, and in another position of the movable wall or part of the wall the flushing water cistern is opened, so that all the flushing water flows over the upper edge of the funnel and along its inner sides, thereby giving a thorough and effective flushing to all the parts in the closet that require rinsing.

An important characteristic of the water closets according to this invention is, that all the flushing water supplied through a float valve, flushing valve or the like, and which will be used for the flushing is collected in a flushing water cistern arranged in the closet itself, which cistern is situated at or above the upper edge of that part of the outlet pipe which is enlarged into a collecting funnel, whereby all the flushing water, when the closet is used, is caused to flow from the flushing water cistern over the

upper edge of the funnel and along its inner sides, thereby causing a most effective flushing.

In the accompanying drawing is shown an embodiment of a water closet according to this invention. Fig. 1 shows a vertical section of the closet with the different parts in that position, they assume when the closet is not in use, whereby the flushing water cistern is empty. Fig. 2 shows the upper part of the same closet with the movable part of the seat pressed down and the float valve opened, so that the flushing water may flow into the flushing water cistern. Fig. 3 shows the upper part of the closet with the movable part of the seat still pressed down. The needed amount of flushing water having entered the flushing water cistern, and the float valve being closed.

In the upper part of the closet 1 a cistern 2, the flushing water cistern, is arranged around the upper edge 4 of that part of the outlet pipe which is enlarged to form a collecting funnel 3, above which the cistern is situated. The inner wall 5 of the flushing water cistern situated towards the collecting funnel is formed out of a movable ring 6 in the closet, the closing ring, of the same shape as the upper edge 4 of the collecting funnel. The closing ring 6 is provided with a tightening ring 9 and is supported by springs 8, which normally hold the same in such a position, that the tightening ring 9 is not in touch with the upper edge of the collecting funnel, as shown in Fig. 1, whereby a ring shaped outlet canal 10 from the flushing water cistern 2 is formed. At those times when the closing ring 6 is pressed down, as shown in Figs. 2 and 3, said canal is closed. In the flushing water cistern there is a wall 11 with a number of holes 12. The flushing water reaches the flushing water cistern 2 in the closet 1 through an inlet 13 from a float valve, flushing valve, or flushing cistern joined to said inlet. The seat consists as usual of two parts, the stationary part 14 and the movable part 16, which parts are joined together by a hinge 15, the part 14 being fastened by screws to the closet 1.

The described water closet works in the following manner. When one sits down on the movable part 16 of the seat, the closing ring 6 is pressed down, whereby the springs 8 are compressed, see Figs. 2 and 3. Tight-

ening then takes place between the wall 5 on the closing ring 6 and the upper edge 4 of the collecting funnel 3, so that the flushing water cistern 2 is closed. The flushing water 5 is now supplied to the flushing water cistern through a float valve, flushing cistern or flushing valve, and the said cistern is filled with the amount of water needed for a complete flushing. By the shown embodiment 10 the supplying of flushing water to the flushing water cistern takes place automatically through a float valve 26, provided with a swingable arm 27, the free end of which is provided with a ball float 28, which, when the closet is not in use (Fig. 1), rests on an arm 29 which is movable upwards and downwards and is connected to the locking ring 6. The float valve 26 is opened, so that the flushing water may flow into the cistern 2, when the movable part 16 of the seat is pressed down, Fig. 2, and is closed, when the water in the flushing water cistern 20 has risen so high that the ball float is lifted up to the position shown in Fig. 3. Fig. 1 shows the parts in those positions they assume, when the closet is not being used, whereby the flushing water cistern is empty. When one rises from the movable part 16 of the seat, the pressure on the closing ring 30 6 ceases, and that ring as well as said part of the seat rises owing to the pressing of the springs 8. The canal 10 between the tightening ring 9, and the upper edge 4 of the collecting funnel is opened, and the entire 35 amount of flushing water flows from the flushing water cistern through this canal over the upper edge 4 of the funnel 3 into said funnel, the walls of which are given a very effective rinsing. When the water level 40 in the flushing water cistern 2 has sunk sufficiently the remainder of the flushing water collected in said cistern runs slowly out into the funnel 3, through the holes 12, the height of which is so calculated that the 45 amount of flushing water thus running slowly into the funnel fills it to the height of the water lock, as shown in Fig. 1.

Water closets, arranged according to this invention, may be constructed in many other ways than those given in the example. 50 Thus only a part of the wall 5 of the flushing water cistern need be movable, so large a part however, that the flushing water flows in sufficient force to the collecting funnel and gives it a thorough flushing. The part 55 effecting the tightening may instead of being situated in the movable closing ring 6 as shown be arranged on the upper edge of the funnel 3. Further the movement of the closing member may be different from the one described, for example, as parallel movement in any direction, or turning around a shaft, et cetera. The arrangement for the moving of the wall part 5, may also be made 60 in many other ways. Thus the wall, may act in connection with a lever device, by which it is brought to its different positions. The arrangements for automatically opening the float valve supplying the flushing water or the flushing valve may also be arranged in many other ways than those described. 65

Having now described my invention, what I claim as new and desire to secure by Letters Patent is:

A water closet including an outlet pipe enlarged to provide a collecting funnel, a flushing cistern disposed at the top of the funnel and communicating therewith, said cistern including a movable inner wall, valve 80 controlled means for supplying water to the cistern, said movable wall being adapted when leveled to permit the discharge of water from the cistern into the funnel, and an upstanding wall in the cistern surrounding the movable wall adapted to restrain a part of the water in the cistern, said upstanding wall having perforations therein to permit of the relatively slow discharge of the remainder of the water in the cistern 90 into the funnel.

In witness whereof, I have hereunto signed my name.

ELOF KARL HJALMAR LUNDBERG.
